UNITED STATES PATENT OFFICE.

ROY L. HUSTON, OF CARTERVILLE, MISSOURI, ASSIGNOR OF ONE-HALF TO CHARLES T. CLARK, OF CARTERVILLE, MISSOURI.

CAR-FENDER.

1,216,997.

Specification of Letters Patent. Patented Feb. 20, 1917.

Application filed November 28, 1916. Serial No. 133,369.

To all whom it may concern:

Be it known that I, Roy L. Huston, a citizen of the United States, residing at Carterville, in the county of Jasper and State 5 of Missouri, have invented certain new and useful Improvements in Car-Fenders; and I do hereby declare the following to be a full, clear, and exact description of the invention, such as will enable others skilled in the art 10 to which it appertains to make and use the same.

This invention relates to new and useful improvements in car fenders and the principal object of the invention is to provide a 15 fender adapted to pick up a person struck by the same and thereby avoid the possibility of the person or object getting under the car and becoming entangled in the running gear.

20 Another object of the invention is to provide a safety fender which when a person or object falls thereinto is operated to swing its front panel upwardly in order to avoid the possibility of the person or object rolling out 25 of the front end of the fender and on to the track.

A further object of the invention is to provide a locking means for holding the front panel upwardly which is automatically operated upon the releasing of the fender and which will support the panel in its uppermost or intermediate position until the panel 30 is released.

With these and other objects in view the 35 invention consists in the novel combination and arrangement of parts which will be fully set forth in the following specification and accompanying drawing, in which—

Figure 1 is a fragmentary side view of 40 the front platform of a car showing a fender constructed in accordance with this invention applied thereto.

Fig. 2 is a top plan view of the fender showing the same removed from a car,

45 Fig. 3 is a longitudinal sectional view on line 3—3 of Fig. 1 of the fender showing the front panel partially folded in dotted lines.

Fig. 4 is a transverse sectional view 50 through the fender showing in detail the bump board and mechanism controlled thereby, and

55 Fig. 5 is an enlarged fragmentary detail sectional view of the latch for holding the front panel of the fender in its various positions.

Referring to the drawing the numeral 1 designates a car of the ordinary construction having attached to the front bumpers the fender designated generally by the numeral 2. This fender comprises the side panels 3 and 4 which are connected and held in parallel spaced relation by the rear panels 5 and a bottom panel 6. It will be understood that these panels 3, 4, 5, and 6 may be constructed of frame bars and suitable netting so as to 60 form a support for a person or object when the same falls into the fender. Extending between the horizontal frame bars of the rear panel 5 are suitable vertical supporting bars 7 which are arranged in spaced parallel 65 relation and formed intermediate their ends with enlargements 8 which provide supports for the transversely extending shaft 9 on which the rocker arm to be more fully hereinafter described is pivoted.

The front end of the device is closed by the front panel 10 which is hingedly connected to the forward edge of the bottom 6 as at 11 and is adapted to fold upwardly 70 into a vertical position so as to extend parallel with relation to the rear panel 5 and thus form a complete box like structure into which the person or object falls when struck by the fender. Attached to the upper forward corners of the side panels 3 and 4 are 75 the forwardly extending arcuate arms 12 which are provided with apertures 14, the use of which will appear as the description 80 proceeds.

In order to normally tend to swing the 90 front panel upwardly, suitable retractile coil springs 15 are attached at their forward ends to the upper bar of the front panel 10 while the rear ends of said springs are connected to suitable eyes 16 which surround 95 the upper horizontal bar of the rear panel 5. It will thus be seen that an upward and inward pull will be exerted on the panel which will normally tend to swing the front panel 10 to closed position.

In order to hold the panel in open position, a suitable trip rod 17 is provided and is slidable through an eye 18 supported on the lower forward bar of the bottom panel 6 and this trip rod is provided at its forward 105 end with a hook 18' which engages the bar of the front panel at the free edge thereof to normally hold the same in the positions shown in Figs. 1 and 3. The rear end of this trip rod is bent upwardly as at 19 and 110

provided with an eye 20 which receives a pivot pin 21 in order to pivotally connect the rear end of the trip rod to a lever 22 which is pivotally mounted intermediate its 5 ends to the bar 9. The upper end of the lever 22 has pivotally connected thereto as at 23 a forwardly extending arm 24 which supports at its forward extremity the bumper board 25 which when struck forces 10 the arm 24 rearwardly thereby causing the lever 22 to rock on its pivot and move the trip arm 17 forwardly thus releasing the hook 18' and allowing the springs 15 to swing the front panel to a vertical position. 15 In order to provide a means for holding the panel in its closed or partially closed position, a suitable latch casing 26 is connected to opposite ends of the free edge of the front panel 10 and this latch casing has 20 slidably mounted therein a latch 27 which is normally forced outwardly by a spring 28 so that the tongue 29 of said latch will be moved into contacting engagement with the walls of the openings 14 in the arcuate bars 25 12 and 13.

It will be apparent from the foregoing that when the fender strikes a person or object, the same will be thrown upon the fender and falling against the bumper board 30 25 will rock the lever 22 thus causing the trip bar 17 to move forwardly at which time the hook 18' is disengaged from the front panel thus allowing the same to swing upwardly under the influence of the springs 15 35 and it will be evident that the tongue 29 of the latch 27 will ratchet against the walls of the openings 14 as the panel swings upwardly and when the panel comes to a stop it will be seen that the tongues will project 40 through certain of the openings 14 thus firmly locking the panel in closed position.

While in the foregoing there has been shown and described the preferred embodiment of this invention, it is to be understood that such changes may be made in the combination and arrangement of parts as will fall within the spirit and scope of the invention as claimed.

What is claimed is:—

50 1. A fender comprising a substantially box like structure having a hinged front wall, springs normally urging said front wall upwardly to closed position, a trip mechanism for holding said wall in open position, means to release the trip mecha-

nism, means to lock the wall in closed position when moved upwardly, and a bumper board adapted to be engaged by an object when the same falls into the fender for releasing the trip means. 60

2. A fender comprising a box like structure adapted to be attached to the forward end of a vehicle, a hinged panel closing the forward end of the box like structure, a rocking lever at the rear end of the box like 65 structure, an arm extending forwardly from the lever into the box like structure, a bumper board at the forward end of the arm, a trip bar extending beneath the box like structure and having its rear end connected to the lower end of the rocking lever, a hook at the forward end of the trip bar adapted to engage the front panel to hold the same in lowermost position, springs to urge the panel to closed position and means 70 to hold the panel in closed position after the trip bar has been operated to release said panel. 75

3. A fender comprising a box like structure adapted to be attached to the forward end of a vehicle, a hinged panel closing the forward end of the box like structure, a rocking lever at the rear end of the box like structure, an arm extending forwardly from the lever into the box like structure, a bumper board at the forward end of the arm, a trip bar extending beneath the box like structure and having its rear end connected to the lower end of the rocking lever, a hook at the forward end of the trip bar adapted 80 to engage the front panel to hold the same in lowermost position, springs to urge the panel to closed position and means to hold the panel in closed position after the trip bar has been operated to release said panel, arcuate 85 bars extending forwardly and downwardly from the upper forward corners of the box like structure, said arcuate bars being provided with apertures and latches carried by the forward panel for engaging in the apertures of the arcuate bars to lock the panel in its uppermost position after the trip bar has 90 been released. 95

In testimony whereof I affix my signature in presence of two witnesses.

ROY L. HUSTON.
